VARIABLE ANGLE MAGNETIC DRIVE

Edward P. Kupka, Berwyn, Ill., assignor to General Motors Corporation, Detroit, Mich., a corporation of Delaware

Application April 18, 1955, Serial No. 501,886

5 Claims. (Cl. 310—105)

This invention relates generally to variable angle drives and more particularly to features which enable the drive to take different angular positions during operation of the drive.

Quite often in the use of rotatable booms, as for example booms for dredges and the like, it is common to provide a separate drive motor or engine directly on the boom as a means for driving a cutting head. Although the present invention is not so limited, one of its possible applications would be for the elimination of such a separate drive motor or engine directly from the boom.

It is, therefore, an object of the present invention to provide a universal angle drive between driving and driven members whose drive angle can be varied over a wide range during the course of operation of the driving and driven members.

This and other objects of the invention will appear in more particularity upon reference to the accompanying detailed description and drawing, in which:

Fig. 1 represents an application of the invention and illustrates the use of the drive between a driving motor and the cutting head carrying boom of a dredge.

Fig. 2 is an enlarged side view in elevation of the novel variable angle drive illustrating how the use of gimbal pieces allows the widely variable operating positions of the drive.

Fig. 3 is an end view in elevation further illustrating the use of the gimbal pieces.

Fig. 4 is a plan view in section taken on the line 4—4 of Fig. 3 also illustrating the use of the gimbal pieces and other details of the angle drive.

Referring now to the drawing and particularly to Fig. 1, a dredge 2 is shown having a derrick 4 mounted thereon. Below the derrick 4 is a drive motor 6 which by means of the novel universal angle drive indicated generally by a numeral 8 is operatively connected to a rotatable dredge boom 10. As indicated by the broken lines in Fig. 1, the boom 10 is movable in a conical manner by means of guys 12. The boom is provided with a cutting head 14.

Referring now to Figs. 2, 3 and 4, it will be observed that the boom shaft is adapted to be rotated about its longitudinal axis by the drive motor 6 through the universal angle drive indicated generally by the numeral 8. This drive includes includes a pair of transversely spaced supports 16 in which the trunnions 18 of a gimbal ring or piece 20 are supported for movement of the ring about an axis 22 extending through the point 24. A second gimbal piece or ring 26 is supported by means of trunnions 28 for movement about an axis 30 in the same plane as the axis 22 and at right angles thereto. Axis 30 also extends through the point 24. The gimbal piece 26 is provided with a circular bearing opening 32 whose axis also extends through the point 24 and is always perpendicular to the axis 30. Journalized for rotation in the opening 32 is one end of the dredge boom 10 which has fixed thereon a spherical driven coupling member 34. Coupling member 34, as already mentioned, is spherical

in shape and has inner and outer spherical surfaces 36 and 38, respectively, which are generated by radii about the point 24. The member 34 is of magnetizable material and forms the inductor ring of an eddy current coupling.

- 5 Fixed on an extension 40 of the drive shaft of the driving motor 6 is a female member 42 having a plurality of interdigitated poles 44. The poles 44 are provided with convex spherical surfaces 46 generated by equal radii about the point 24. Since the spherical surfaces 10 38 and 46 have been generated about centers coincident with each other and the surfaces have been spaced from each other by an air gap 48, this air gap is uniform throughout between these surfaces. The poles 44 are interlaced about a field exciting coil 50 which may be 15 energized through suitable slip rings, not shown, to generate a toric flux which interlinks both members 34 and 42 and passes through the polar members 44 and the inductor surface 38 and the polar members 44 which also are magnetic. It will be observed that the axis of 20 rotation of the shaft 40 and of the polar member 42, as well as the field exciting coil 50, also extend through the point 24.

By combining this spherical eddy current coupling with a pair of gimbal pieces, an infinitely variable universal 25 angle drive has been provided whose angle can be varied during operation of the drive thereby achieving a flexibility of operation, as for example in the boom of a dredge, which heretofore was not available. It will be observed that this infinitely variable drive includes no 30 mechanical parts actually connecting the driving member with the driven member of the drive and that all of the weight of the boom is taken up through the gimbal pieces 20 and 26 and the supports 16 thereby placing no loading strains or stresses on the drive itself, whose sole function, 35 then, is to drive the boom.

What I claim is:

1. A constant velocity ratio universal coupling for effecting a variable angle mechanical drive comprising a support, male and female driving and driven members 40 rotary on variable angled axes having an intersecting point, a gimbal piece on said support oscillatory about an axis through said point during driving of said driven member by said driving member, a second gimbal piece mounted on said first gimbal piece oscillatory about an axis through 45 said point perpendicular to the axis of movement of said first gimbal piece during driving of said driven member by said driving member and journaling one of said members, one of said members having flux concentrating polar members the outer peripheries of which are defined spherically with a center substantially at said point, the other member having an adjacent relatively uninterrupted inductor surface also defined spherically with a center substantially at said point, the resulting spherically defined polar peripheries of the flux concentrating polar members 50 and said spherically defined conductor surface being spaced by means of a constant spherical air gap irrespective of the angle of said axes, and at least one annular excitation coil carried on one of said members in a plane substantially perpendicular to its axes of rotation and generating a toric flux field interlinking both of said members and passing through said polar members and through said inductor surface, the inductor surface and the polar members being magnetic.

2. A constant velocity ratio universal coupling for effecting a variable angle mechanical drive during operation of said drive comprising a support, male and female driving and driven members rotary on variable angled axes having an intersecting point, a gimbal piece on said support oscillatory about an axis through said point, a second gimbal piece mounted on said first gimbal piece oscillatory about an axis through said point perpendicular to the axis of movement of said first gimbal piece and

journaling said male member, one of said members having flux concentrating polar members the outer peripheries of which are defined spherically with a center substantially at said point, the other member having an adjacent relatively uninterrupted inductor surface also defined spherically with a center substantially at said point, the resulting spherically defined polar peripheries of the flux concentrating polar members and said spherically defined conductor surface being spaced by means of a constant spherical air gap irrespective of the angle of said axes, and at least one annular excitation coil carried on one of said members in a plane substantially perpendicular to its axes of rotation and generating a toric flux field interlinking both of said members and passing through said polar members and through said inductor surface, the inductor surface and the polar members being magnetic.

3. In combination with an eddy current coupling including spaced magnetic spherical rotatable driving and driven members having a common point about which their spaced spherical surfaces are generated, a support, and a universal joint supporting one of said members for universal movement about said point during driving of the driven member by the driving member.

4. In combination with an eddy current coupling including spaced magnetic spherical rotatable driving and

driven members, a support, and a universal joint supporting one of said members for universal movement relative to the other of said members during driving of the driven member by the driving member.

5. In combination, an eddy current coupling including spaced magnetic spherical rotatable driving and driven members, said members having a common point about which their spaced surfaces are generated, a support, a gimbal piece oscillatory on said support about an axis, 10 a second gimbal piece oscillatory with respect to said first gimbal piece about an axis intersecting said first axis at right angles thereto and means journaling one of said members in said second gimbal piece for rotation about an axis perpendicular to and extending through the intersection of said first two axes.
